Primary Examiner—Sandra Snapp*Assistant Examiner*—Patricia Palasik(74) *Attorney, Agent, or Firm*—Howard & Howard Attorneys PLLC(57) **CLAIM**

The ornamental design for a vibratory screen panel, as shown and described.

DESCRIPTION

FIG. 1 is a front elevational view of a vibratory screen panel showing my new design;

FIG. 2 is a right side elevational view thereof;

FIG. 3 is a top plan view thereof;

FIG. 4 is a left side elevational view thereof;

FIG. 5 is a back side elevation view thereof;

FIG. 6 is a bottom plan view thereof

FIG. 7 is an enlarged detailed view of the vibratory screen panel as shown in circle 7 in FIG. 3; and,

FIG. 8 is a top perspective view thereof.

The broken away portions shown in FIGS. 2, 3, 4, 6 and 8 indicate indeterminate width.
